UNITED STATES PATENT OFFICE.

CHARLES F. SIMMS, OF ATTLEBORO, MASSACHUSETTS, ASSIGNOR TO WATSON & NEWELL COMPANY, A CORPORATION OF RHODE ISLAND.

DESIGN FOR A HANDLE FOR SPOONS, FORKS, OR SIMILAR ARTICLES.

42,775.

Specification for Design.

Patented July 9, 1912.

Application filed December 28, 1911. Serial No. 668,303. Term of patent 3½ years.

To all whom it may concern:

Be it known that I, CHARLES F. SIMMS, a citizen of the United States, and residing in the town of Attleboro, in the county of Bristol and State of Massachusetts, have invented a new, original, and ornamental Design for a Handle for Spoons, Forks, or Similar Articles, which is illustrated in the accompanying drawing, forming part of this specification.

Figure 1 of the drawings is a front elevation, or view of the obverse side of a spoon

embodying my present design, and Fig. 2 is a sectional perspective view of the obverse side of the spoon handle taken on the line 2—2, Fig. 1.

What I claim is:—

The ornamental design for a handle for spoons, forks or similar articles as shown.

CHARLES F. SIMMS.
